UNITED STATES PATENT OFFICE

131,574

DESIGN FOR A TABLECLOTH OR SIMILAR ARTICLE

Will Funston, New York, N. Y.

Application January 20, 1942, Serial No. 105,327

Term of patent 3½ years

To all whom it may concern:

Be it known that I, Will Funston, a citizen of the United States of America, residing in New York city, county of New York, and State of New York, have invented a new, original, and ornamental Design for a Tablecloth or Similar Article, of which the following is a specification, reference being had to the accompanying drawing, forming part thereof, wherein, the figure of the drawing is a plan view of a tablecloth or similar article, showing my new design.

I claim:

The ornamental design for a tablecloth or similar article, substantially as shown.

WILL FUNSTON.
